PICKER STICK SUPPORT

Harold Hoeber, South Dartmouth, Mass.

Application January 16, 1942, Serial No. 427,041

7 Claims. (Cl. 139—150)

This invention relates to fly shuttle looms and more particularly to means for securing a picker stick to such a loom in a manner which will permit the position of the picker readily to be adjusted in relation to other operative parts.

In a loom where the shuttle is driven across the lay by a blow from a picker, it is well known that the position of the picker relative to the shuttle during impact is important, and must be controlled within close limits. It is usual practice fixedly to attach the picker to an end of the picker stick, and to place the other end of the picker stick in a holding means, such as the parallel shoe. It has been proposed heretofore to make the connection between the picker stick and the parallel shoe of such a nature as to enable the picker stick to be slipped along the connecting member by a manual operation to place the picker in approximately the correct position before securing the parts in place. By such means it is difficult to make a correct adjustment of the picker without considerable manipulation of the related parts.

It is an object of this invention to provide means associated with a picker stick which will enable the position of the picker stick, and therefore the picker, to be adjusted under positive control and to be fixedly secured in the adjusted position.

It is a further object of this invention to secure a member to the picker stick and connect it in an adjustable manner with a parallel shoe formed to receive the picker stick so that the position of the latter relative to the shoe can be controlled by manipulating the connection.

It is another object of this invention to provide a picker stick having means at one end to assure that the picker will be placed on the stick in a predetermined position, and means at the other end whereby the picker stick can be placed in a holding means and adjusted in relation thereto before being secured in operative position.

These and other objects may be accomplished by the construction shown in the accompanying drawing in which:

Fig. 1 is a front elevation of a portion of the replenishing side of a loom, with my invention applied thereto.

Fig. 2 is a front elevation, partly in section, of a picker stick and picker stick holding means made in accordance with my invention.

Fig. 3 is a perspective view of the picker stick holding means shown in Fig. 2, to an enlarged scale.

Fig. 4 is a plan view of a detail of the device, taken on the line 4—4 of Fig. 2.

The drawing shows an embodiment of my invention applied to a filling replenishing loom of well known construction, although it is to be understood its use is not limited thereto. The loom may comprise a loom side 1 having a magazine 2 mounted thereon from which reserve filling carriers 3 are transferred to a shuttle 4.

One end of a picker stick 5 is attached to a parallel shoe 6 which rocks on a parallel 7. The parallel is attached to a rocket shaft, not shown, which causes the parallel, and hence the picker stick, to reciprocate forwardly and rearwardly of the loom in synchronism with the lay 8.

The picker stick is actuated longitudinally of the lay by a lug strap 9 attached to a suitable driving mechanism, not shown.

A picker 10 is attached to the other end of the picker stick in a position to contact one end of the shuttle 4 to drive the shuttle across the lay.

All of the foregoing construction is well known in the art and forms no part of the present invention.

It is usual practice to form a cup 11 in the face 12 of the picker to receive the end of the shuttle in close cooperation when the shuttle enters the shuttle box. The shuttle enters the box with some force and the end of it seats itself forcibly in the cup 11. If the picker is properly adjusted, the center of the cup 11 will be in line with the longitudinal center of the shuttle, and, on contact, the shuttle will maintain a position parallel with the lay and seated thereon throughout its length. When it is picked from the box the shuttle will make a smooth flight through the shed and seat itself properly in the box on the opposite end of the lay.

However, if the picker is not properly adjusted, when the end of the shuttle is seated in the cup 11 the shuttle will not assume a horizontal position. If the picker should be too low the outer end of the shuttle, that is the end contacting the picker, will be depressed, causing the opposite end thereof to be raised. If this condition is aggravated the inner end of the shuttle may be pushed against the top of the box, thereby increasing the frictional resistance on the shuttle and reducing the effective force of the pick.

If the position of the picker is too high the outer end of the shuttle will be elevated and the inner end depressed, again causing the shuttle to be improperly boxed and the frictional resistance thereon increased.

In either case much of the force of the picker

will be used to overcome the increased resistance on the picker and less will be available to drive the shuttle across the lay. If the shuttle does not enter the box on the opposite end of the lay with sufficient force it will not be able to overcome the designed braking resistance of the shuttle box enough to enter it fully. If the shuttle is not properly boxed the effective effort of the picker is again reduced. The condition is cumulative and soon causes a stoppage of the loom.

In some cases an improperly adjusted picker will cause the flight of the shuttle to become erratic, and the shuttle will "lope" through the shed, that is, follow a sinusoidal path instead of a straight line. Where the deviation of the shuttle from a straight path is pronounced, the shuttle may contact the warp threads alternately on the bottom and top of the shed and cause an injury thereto which may result in a defect in the cloth. In extreme cases the shuttle may be caused to leave the shed, rupturing warp threads and disrupting the operation of the loom.

It also has been found that an improperly adjusted picker has a much shorter life than one which is properly adjusted. The continued hammering contact of the shuttle point on but one side of the cup 11 soon causes the walls of the picker on the contact side to break down, and the usefulness of the picker to be destroyed.

Attempts have been made to adjust the picker by changing its position on the picker stick. To do this it is necessary to remove the screw 13, which is normally used to hold the picker securely in place, and to form another hole in the picker stick to receive it in the new position. After a few such changes the picker stick becomes perforated with holes in the tip portion within the range of possible adjustment of the picker. The screw 13 is then unable to find a purchase in the stick by which to hold the picker in yet another position, and when this occurs the usefulness of the picker stick is at an end.

The present invention provides a means for readily and accurately adjusting the position of the picker without removing it from the picker stick or damaging the related parts.

The bottom portion of the picker stick is supported in a parallel shoe 6 which rocks on a parallel 7. The parallel shoe has an opening 14 through it from top to bottom of such size as to receive the picker stick, and there is a corresponding opening in the parallel for the same purpose. The picker stick projects through the openings in the parallel shoe and parallel and extends below the latter where it is engaged by a strap 15 extending to a spring drum 16.

Also extending through the openings in the parallel shoe and parallel, and placed between a wall of the openings and the picker stick, is a member 17, which may be called a tongue.

The shoe 6 has an upwardly projecting flange 18 thereon, forming an extension of one wall of the opening 14. The tongue 17 is placed between this flange portion and the picker stick. The flange 18 has an opening 19 therein to receive a bolt 20. The tongue has an opening 21 in line with the opening 19 and for a similar purpose.

The picker stick in the region in axial alignment with the openings 19 and 21 has a slot 22 formed in it, having a dimension longitudinally of the picker stick several times that of the bolt 20. The slot 22 is designed to receive the bolt also. In assembling, the bolt is passed through the holes 19 and 21 and through the slot 22 until it extends from the picker stick on the opposite side.

An end of the strap 15 is engaged over the bolt and a washer 23 is placed thereon. A lock washer 24 and nut 25 complete the assembly.

Threaded through the flange in a position above the bolt 20 is a set screw 26. The tip 27 of the set screw abuts the tongue 17 and provides a means for controlling the angular position of the tongue and the picker stick relative to the parallel shoe. A nut 28 is provided on the set screw to abut the face of the flange 18 to hold the set screw in its adjusted position.

The upper portion of the tongue 17 has a projection 29 formed thereon. The projection has a vertical hole 30 formed in it, tapped to receive a bolt 31.

Spaced above the tongue 17 there is secured to the picker stick a U shaped member 32, the legs 33 and 34 of which are screw threaded to receive nuts 35 and 36. Placed between the base of the U shaped portion and the picker stick is an element 37, one end of which is arcuate in form to fit snugly within the U and the other end of which is flat to engage the edge of the picker stick.

The element 37 has an opening 38 through it, large enough to receive the bolt 31. The bolt passes freely through the opening and is revolvable therein. A slot 39 may be cut in the element 37 communicating with the opening 38 and of such dimensions that the bolt 31 can be inserted in the opening by passing it through the slot.

The element 37 has a groove in its periphery to receive the member 32 to aid in securing the parts in place.

On the opposite side of the picker stick from that engaging the element 37, a strip of resilient material 40 is placed astraddle the legs 33 and 34, and this is backed up by a bar of rigid material, which is engaged by lock washers 42 and 43 and the nuts 35 and 36 to complete the assembly. By tightening the nuts 35 and 36 the element 37 is securely fastened to the picker stick.

The bolt 31 has a head 44 abutting the top face 45 of the element 37. The bolt passes through the opening 38 and a nut 46 is screwed onto the bolt until it approaches the lower face 47 of the element 37. When the head 44 and nut 46 are so spaced that the element 37 can fit between them with sufficient clearance to allow the bolt easily to be turned, the nut 46 is secured in place, as by brazing it to the bolt, as shown at 48.

A second nut 49 is threaded on the bolt followed by a lock washer 50. The bolt is then threaded in the opening 30 in the projection 29.

When the members 32 and 37 are assembled the bolt will be held in place on the member 37 but will be freely revolvable relative thereto.

It will be seen from this construction that as the bolt is threaded into or out of the opening 30, the member 37 will follow it, and a means is thereby afforded for adjusting the relative distance between the aforesaid member 37 and the tongue 29. Since the member 37 ordinarily is rigidly attached to the picker stick, and since the tongue is held in a position relatively stationary to the parallel shoe by the bolt 20, if the nut 25 is loosened to permit the picker stick to move relative to the tongue and shoe, by adjusting the bolt 31 the picker stick also will be adjusted in position relative to the parallel shoe. When the desired adjustment is obtained the nut 25 on bolt 20 and the nut 49 on bolt 31 can be tightened into place to hold the picker stick and the parallel shoe fixedly in the new position.

By this invention all of the necessary adjust-

ments of the picker can be made at the base of the picker stick. In order to assure that the picker always will maintain a fixed position on the top of the picker stick a projecting element 51 is attached to the top of the stick in a position to abut the bottom of the picker. The member 51 may be a dowel inserted in an appropriate hole formed in the picker stick with a part left projecting beyond the face thereof. The member 51 is placed in spaced relationship to the tip of the stick to allow sufficient space for the picker to be placed thereon. A holding means, such as the screw 13, is provided to hold the picker in place.

Now it will be seen that the picker fixed in position on the top of the picker stick, as the position of the latter is adjusted the position of the picker necessarily must change. By manipulating the adjustable connections at the base of the picker stick the picker can be placed in any desired location, and can readily be brought in alignment with the shuttle.

Having thus described a preferred embodiment of my invention, I claim:

1. A support for a picker stick comprising a means having an opening therein to receive said picker stick, an element in said opening between said means and said picker stick, a second element, said second element being secured to said picker stick, and an adjustable connection between said elements whereby the position of said second element and said picker stick can be adjusted vertically relatively to said first element.

2. A support for a picker stick comprising a parallel shoe, an opening through said shoe arranged to receive said picker stick, an element in said opening between said picker stick and said shoe and slidably engaging said picker stick, a second element secured to said picker stick above said first element and in spaced relationship therewith, and an adjustable connection between said elements, whereby the position of said picker stick and said second element can be adjusted relatively to said first element.

3. A support for a picker stick comprising a parallel shoe, an opening through said shoe arranged to receive said picker stick, an element in said opening between said picker stick and said shoe and slidably engaging said picker stick, a second element secured to said picker stick above said first element and in spaced relationship therewith, and means revolvably mounted in said second element and connected by screw threads to said first element whereby said second element and said picker stick can be adjusted in position relative to said first element.

4. A support for a picker stick comprising a parallel shoe, an opening through said shoe ar-

ranged to receive said picker stick, an element in said opening between said picker stick and said shoe and adjustably engaging said picker stick, a second element secured to said picker stick above said first element and in spaced relationship therewith, an adjustable connection between said elements whereby the position of said picker stick and said second element can be adjusted relative to said first element, and means to secure said elements, said picker stick, and said parallel shoe in an adjusted position.

5. A support for a picker stick comprising a means arranged to receive one end of said picker stick in adjustable relationship, an element secured to said picker stick and having an adjustable connection with said means, said adjustable connection being arranged to permit the relative positions of said means and said element to be adjusted longitudinally of the picker stick, and means fixedly to secure said first means and said picker stick in an adjusted position.

6. A means for supporting a picker stick comprising a member having an opening therein to receive one end of said picker stick, an element in said opening between said member and said picker stick and adjustably engaging said picker stick, a second element, said second element being secured to said picker stick, an adjustable connection between said elements and arranged to permit the relative positions of said elements to be adjusted longitudinally of the picker stick, and means to secure said member, said elements and said picker stick in an adjusted position.

7. A support for a picker stick comprising a shoe, an opening in said shoe arranged to slidably receive said picker stick, a tongue in said opening positioned between said shoe and said picker stick, said tongue and said shoe having openings there-through to receive a bolt, said picker stick having a slot there-through corresponding in position with said openings and arranged to receive said bolt, said bolt being arranged to hold said shoe and said tongue in relatively fixed positions, said slot in said stick being arranged to permit the said stick to move relatively to said tongue and said shoe in a direction longitudinally of said stick, a member secured to said stick in a position above said tongue and in spaced relationship therewith, an adjustable connection between said member and said tongue arranged to permit said member and the said stick secured to it to be adjusted in longitudinal position relative to said tongue and said shoe, said bolt being arranged to permit said picker stick, said tongue, and said shoe to be fixedly secured in their adjusted positions.

HAROLD HOEBER.
